MASSAGE MACHINE

Robert H. Hamblin, Indianapolis, Ind., assignor
to Gro-Flex Corporation, Indianapolis, Ind., a
corporation of New York

Application October 28, 1933, Serial No. 695,569

5 Claims. (Cl. 128—46)

The invention relates to massage machines and has for its object, in general, to improve the device disclosed in the copending application of Robert H. Hassler, filed July 29, 1933, 5 Serial No. 682,739.

In the copending application, as in the present application, the type of massage machine under consideration is one which is preferably motor driven and in which the massaging action is produced by an annularly rocking or wobbling applicator. For reasons which are fully pointed out in the copending application, it is of the highest importance to prevent the applicator from slipping upon or rubbing the massaged surface, particularly when the device is used for massaging the human scalp.

One object of the invention is to provide improved means for preventing the rotary movement of the driving mechanism from being imparted to the applicator while permitting the translation of such rotary movement into the annular rocking movement of the applicator.

A further object is to enhance the safety, appearance and compactness of machines of this nature by enclosing within a substantially continuous housing, all gearing and all regions of the device in which rocking and stationary parts are in proximity to one another.

In the accompanying drawings there is shown an illustrative embodiment of the invention which will now be described.

Figure 1 shows, in side elevation, my improved massage unit, mounted upon a chair and applied to a user's head;

Figure 2 is an enlarged vertical section in the plane of symmetry, a portion of the applicator being in elevation;

Figure 3 is a view similar to Figure 2, the parts being in a different phase of operation and portions of the applicator and housing being in elevation;

Figure 4 is a longitudinal section, further enlarged, of certain parts shown in Figures 2 and 3 and in the same plane;

Figure 5 is a section on line 5—5 of some of the parts shown in Figure 4;

Figure 6 is a cross-section on line 6—6 of Figure 4; and

Figure 7 is a cross-section on line 7—7 of Figure 3.

Referring generally to the device shown in Figure 1, it comprises a chair 1, supporting post 2, bracket 3, head rests 4, and massage unit 5 with its applicator 6. The present invention re-

sides in the massage unit per se and the remaining parts will be only briefly described.

On the side of the chair, within reach of the user's hand, is a switch 7 which is in circuit, through wiring mainly concealed in the chair, with a source of electric current and with a motor housed in the unit 5. Also within reach of the user is a crank 8 by means of which he can raise or lower the massage unit, suitable gearing for this purpose being housed within the chair and connecting crank 8 with reciprocable supporting post 2.

Bracket 3 is removably attached to post 2 and terminates inwardly in a yoke 9 which embraces and rigidly supports massage unit 5. A pair of padded head rests 4 are carried respectively by yoke arms 10 of yoke 9 which is pivotally supported upon bracket 3.

The massage unit is supported by and housed in a three-part casing comprising a lower member 12, bolted to yoke 9, an intermediate member 13, and a cap or cover 14. The intermediate member 13 has an irregularly shaped integral partition 15 upon which are formed bearings 16, 17 for the shaft 18 of motor 19. A worm on the right-hand end of shaft 18 is in mesh with a gear 20 which is keyed to shaft 21 rotatably supported by ball bearing 22 and guided by ball bearing 23. A gear 24 is keyed to the lower end of shaft 21.

Partition 15 has a central boss 25 to which is secured by nut 26 a hub 27 which has an external radial flange 28. Upon flange 28 rests the inner race 29 of a ball bearing whose outer race is 30. Ring 31 has an internal flange 32, 35 by means of which the ring is supported upon race 30, and an external flange 33, to which is secured by bolts 34 the internal flange 35 of a drum member 36.

A large internal gear 37 is seated on a shoulder 38, formed on drum member 36, and is held against rotation relative to the drum member by rivet-pins 39. Gear 37 is in mesh with gear 24, previously mentioned. When the motor is running the rotation of its shaft 18 will be transmitted through gear 20, shaft 21, gear 23, gear 37, to drum member 36, which rotates freely upon stationary hub 27.

A lower drum member 40 is joined at its periphery to drum member 36 and has a transverse wall 41 which is disposed in a plane oblique to the axis of rotation of the drum members. Wall 41 has an eccentric opening 42 around which is seated a ball bearing comprising outer race 43 and inner race 44. The outer race is held in 55

fixed position upon wall 41 by clamping ring 45. Hub 46 is in shouldered engagement with inner race 44 and has an integral bolt 47 which projects through a spacing collar 48 and through an applicator holder 49. Between the applicator holder and flange 50 on collar 48 is confined inner race 51 of a ball bearing whose outer race is 52. Hub 46, inner races 44 and 51, spacing collar 48, and applicator holder 49 are clamped together axially 10 by means of nut 53.

Applicator 6, preferably of soft rubber, has a central boss 54 provided with a flexible flange 55 which overlies flange 56 on holder 49. Outwardly the boss on the applicator is loosely confined by 15 rim 57 on ring 58, the latter being riveted to reverse-angled ring 59 which hangs upon ball race 52.

It will be understood that when the drum composed of members 36 and 40 is rotating, the 20 applicator will have imparted to it the desired annular rocking or wobbling movement. But for the best results, means must be provided to restrain the applicator from rotating upon its own axis and the means disclosed herein is an important improvement over the corresponding 25 means disclosed in the above-mentioned application of Hassler. Such means comprises, in combination with parts and relations of parts heretofore described, a linking device which connects 30 the hubs 27 and 46. This linking device will now be described.

Hubs 27 and 46 have axial recesses 60, 61, respectively, presented inwardly or toward each other. These recesses constitute seats or 35 housings for a pair of gimbal joints, the outer frames of which are designated 62, 63. In Figures 4 to 6 the details of the upper gimbal joint are shown and it may be assumed that the lower gimbal joint is of similar construction. The specific 40 form of the gimbal joints and of their mounting is not of the essence of the invention, however. Moreover, it should be understood that the term "gimbal joint" is employed here and in the appended claims in a generic sense to include any 45 universal joint which prevents the joined members from rotating upon their own axes relatively to one another.

Referring to the upper gimbal joint in detail, frame 62 is in the form of a ring, internally 50 squared, and having diametrically opposed bores 64 in which are seated bushings 65. Shouldered trunnion studs 66 have their reduced ends seated in bores in the wall of hub 27 and their enlarged ends in bushings 65. At ninety degrees to studs 55 66 is a journal pin 67 whose ends are seated in frame 62. Pin 67 carries bushings 68 and the latter lie in a cross-head 69 which has a stud 70. A sleeve 71 fits over stud 70 at one end and over a similar stud 72 belonging to the lower gimbal 60 joint at the other end. As indicated in Figure 7, the studs and sleeve are of elliptical cross-section which renders those parts non-rotatable with respect to each other. A through-pin 73 holds the sleeve on stud 70 but to facilitate assembling 65 there is no corresponding pin through stud 72. Moreover, the telescopic engagement of the sleeve with stud 72 permits of slight variations in the distance between the centres of the gimbal joints as the parts revolve, although theoretically there 70 need be no such variation.

It will be observed that drum member 40 has a downward extension 74 which terminates in an irregularly shaped flange 75. This flange lies in a plane which is transverse to the axis of rotation of the drum and casing 12 has a complementary flange 76 lying in the same plane in close proximity to flange 75. By this means the annular zone lying between the applicator mounting and casing 12 is blocked off to prevent the insertion of any object into said zone from without. This eliminates the possibility of injury to the user's fingers or to the machine which might otherwise result from the alternate expansion and contraction of said zone at a given point as the eccentrically mounted applicator assembly 15 revolves. Moreover, the appearance of the machine is enhanced by reducing to a minimum the number of rocking parts which are exposed to view. The applicator proper is necessarily exposed, but the rocking and orbital movements of 20 wall 41 and of the applicator mounting are concealed, being translated, so far as visibility is concerned, into the simple rotary movement of flange 75.

I claim:—

1. A massaging machine comprising, in combination, a support having a hub, a frame rotatably mounted on said hub and having a bearing whose axis is oblique to the axis of rotation of the frame, an applicator journaled in said bearing, and means connecting said hub and applicator to permit universal rocking of the applicator with respect to the support while preventing rotation of the applicator relative to the support. 25

2. A massaging machine comprising, in combination, a support having a hub, a frame rotatably mounted on said hub and having a bearing whose axis is oblique to the axis of rotation of the frame, an applicator journaled in said bearing, and a link member connected at one end through a gimbal to said support and at the other end through a gimbal to said applicator. 35

3. A massaging machine as defined in claim 2, in which the axes of the first-mentioned gimbal intersect the axis of rotation of the frame and 45 the axes of the second gimbal intersect the axis of the applicator.

4. A massaging machine comprising, in combination, a casing open at one end, a hub supported within the casing, a frame rotatably mounted at one end on said hub and having at its other end a bearing whose axis is oblique to the axis of rotation of the frame, an applicator journaled in said bearing and projecting through the open end of said casing, and means enclosed by said frame and connecting the hub and applicator to permit universal rocking of the applicator with respect to the support while preventing rotation of the applicator relative to the support. 50

5. A massaging machine comprising, in combination, a casing open at one end, a frame rotatably mounted in said casing and having an element disposed in a plane oblique to the axis of rotation, an applicator carried by said obliquely disposed element and projecting beyond said casing, and an annular shield carried by said frame, said shield surrounding the internal portion of said applicator and terminating in the transverse plane in which the open end of said casing lies. 65

ROBERT H. HAMBLIN.
